US0D1108621S

(12) **United States Design Patent** (10) **Patent No.:** **US D1,108,621 S**
(45) **Date of Patent:** **** Jan. 6, 2026**

(54) **CHASTITY CAGE**

(71) Applicant: **Shenzhen Olina Technology Co., Ltd.**,
Guangdong (CN)

(72) Inventor: **Nana Zheng**, Guangdong (CN)

(**) Term: **15 Years**

(21) Appl. No.: **29/933,590**

(22) Filed: **Mar. 20, 2024**

(51) LOC (15) Cl. **24-01**

(52) U.S. Cl.

USPC **D24/105**

(58) **Field of Classification Search**

USPC D24/215, 200, 211, 214, 133, 107, 231,
D24/105, 121-125

CPC .. A61F 5/0096; A61F 6/04; A61F 5/37; A61F
2005/414
